Primary Examiner — Shannon W Morgan*Assistant Examiner* — Altaira J Swangin(74) *Attorney, Agent, or Firm* — Schmeiser, Olsen & Watts, LLP(57) **CLAIM**

The ornamental design for a hairdressing apparatus, as shown and described.

DESCRIPTION

FIG. 1 is a Front elevational view of a hairdressing apparatus showing my new design;

FIG. 2 is a Rear elevational view thereof;

FIG. 3 is a Left side view thereof;

FIG. 4 is a Right side view thereof;

FIG. 5 is a Top plan view thereof;

FIG. 6 is a Bottom plan view thereof; and,

FIG. 7 is a perspective view thereof.

The broken lines illustrate portions of the hairdressing apparatus and form no part of the claimed design.
